UNITED STATES PATENT OFFICE.

EDUARD RUNGE, OF BERLIN, GERMANY.

CASH-REGISTER.

SPECIFICATION forming part of Letters Patent No. 599,734, dated March 1, 1898.

Application filed June 8, 1897. Serial No. 639,907. (No model.)

To all whom it may concern:

Be it known that I, EDUARD RUNGE, a subject of the Emperor of Germany, and a resident of 31 Brückenallee, Berlin, in the Empire of Germany, have invented a new and useful Cash-Register, of which the following is a full, clear, and exact description.

This invention relates to a cash-register with adding apparatus the keyboard of which has a key for each of the different rows or series of figures—for example, for the units, tens, hundreds, &c.—by depressing which a suitable number-drum of an indicating device is set in rotation, in addition to the active counting-disk, so that the number corresponding to the key struck becomes visible through an aperture.

This invention also relates to devices for limiting the stroke of the key-levers and also to devices by means of which while the depressed key-levers are temporarily locked the numbers on the numbered drums, which are rendered visible at each operation of the machine through the apertures, can be read off and checked before the numbered drums are moved back into the original "0" position. The arrangement is such that the disengagement and locking of the keys depend on the opening and closing of the lid of a till or money-drawer, devices being provided for rendering the operation of the key-levers impossible while the till is closed, so that said operation can only be effected on opening the till.

In combination with the cash-register, in accordance with the present invention, there may be further provided a printing apparatus with a numbering mechanism the type-wheels of which are set to correspond with the numbered drums of the cash-register and which produce an impression or copy of the numbers indicated by the cash-register upon a checking-strip, which remains inside the machine, and also upon a receipt-form, which is to be handed to the purchaser.

The invention further comprises the arrangement of step-by-step or ratchet mechanism for the numbering-disks of the adding apparatus, which should be so arranged as to prevent the numbering-disk that is to be advanced from being rotated after each advance

movement beyond the stroke necessary for such advance movement.

The accompanying drawings illustrate, by way of example, a cash-register which is provided with improvements forming the subject of this invention.

Figure 1 is a sectional end elevation of the cash-register with closed till and with the key-levers locked by means of the latter. Fig. 2 is a part elevation of the devices for temporarily locking the key-levers after the same have been depressed. Fig. 3 is a front elevation, in partial longitudinal section, according to Fig. 1, in which there are five similar ratchets for indicating numbers of one to five places of figures and in which the casing, the key-rods, and several other parts are omitted for the sake of clearness. Fig. 4 is a separate view of the devices for limiting the stroke of the key-levers. Fig. 5 is a plan of the devices shown in Fig. 4. Fig. 6 is a separate view illustrating the devices which serve to prevent in a middle position during the operation further rotation (taking place by the action of the ratchet mechanism) of the counting-disks. Fig. 7 is a separate view illustrating the arrangement of two coöperating number-drums, with apparatus serving to advance the same step by step, in front elevation. Fig. 8 is a separate view showing part of the printing apparatus in its operating position. Fig. 9 illustrates the connection of the printing apparatus with the other parts of the apparatus, said parts being in a position of rest. Fig. 10 shows the step-by-step or ratchet mechanism according to Fig. 6 at the end of its operation. Fig. 11 is a partial plan according to Fig. 9.

In the arrangement shown in the drawings the apparatus is provided with five ratchet sets I II III IV V. Each set comprises an adding apparatus, with advance movement for the tens, and an apparatus for indicating for the purpose of checking the numbers that are rendered visible, said numbers being borne by two indicating-drums, one for checking by the seller and the other for checking by the purchaser. The several ratchet sets can be operated independently of each other, but are connected together by transfer mechanisms. Each set is provided with a key 1, which is

- connected (preferably by means of a spring 4) with a rocking lever 3, which is mounted loose on a shaft 2, that is common to all the sets. The rocking lever 3 carries a pawl 5, 5 which engages in the teeth of a ratchet-wheel 6, that is fixed to the shaft 2. The ratchet-wheel 6 is connected in a suitable manner with the counting-disk of the adding device, as will be described hereinafter.
- 10 The devices for limiting the stroke of the key-levers 3 are arranged as follows: On the rocking lever 3 there is pivoted a pawl 7 in such a manner that on striking against a suitable stop it can be caused to engage with 15 the teeth of the ratchet-wheel, Fig. 2, and thereby prevents further movement of the latter, while normally it is raised by means of a spring 8 or the like from off the ratchet-wheel, Fig. 1. Within the range of movement of these pawls 7 there are arranged tipping shafts w' to w^8 , which preferably extend through the whole of the sets (I to V) and are provided on their lower sides with grooves u , such that on the rotation of the 20 rocking lever 3 of any one of the ratchet sets the free end of the corresponding pawl 7 can slide in the said grooves when the tipping shafts w' to w^8 are in their normal positions. Each tipping shaft w' to w^8 is provided with 25 a tappet d , Fig. 4. At a suitable point of the apparatus there are arranged spring-keys or press-knobs k' to k^8 , Fig. 4, which coöperate with the tappets d of the shafts w' to w^8 . On depressing one of the press-knobs—for example, k' —the corresponding shaft w^7 is turned over, so that the groove u moves out of the path of the pawl 7 and the solid or full surface of the shaft w^7 enters the said path. Consequently on a rotation of the rocking lever 30 3 the pawl 7 meets an obstacle in the tipping shaft w^7 , which is turned over by the press-knob k^7 , so that its lower arm enters the teeth of the ratchet-wheel 6 and locks the latter.
- 35 The arrangement shown is provided for reproducing the numbers of the decimal system. The shafts w' to w^8 , with their corresponding press-knobs k' to k^8 , correspond to the numbers "1" to "8." The normal position of 40 the rocking lever 3 corresponds to the figure "0." For the figure "9" a full or solid fixed shaft w^9 is provided, which forms the limit for the greatest stroke of the rocking lever 3. For this shaft w^9 there may be provided, if desired, for the purpose of completing the keyboard of the apparatus, a fixed or "blind" key k^9 , Fig. 4. In order to return the rocking lever 3 into its initial position after each stroke produced by the depression of the key 45 1, there is employed a spring 18, which is fixed to the arm 17 of the rocking lever 3 and which is tensioned by rotation of the rocking lever and has then the tendency to turn the rocking lever back in the opposite direction. Movement beyond the "0" position is prevented by means of a stop 19. In front of the shaft w' there is further provided

a tipping shaft w^0 , such that in the position of rest of the apparatus it turns its full or solid surface toward the pawl 7, so that automatic or unintentional movement of the rocking lever and of the ratchet-wheel 6 from the "0" position is prevented. On the rotation, which takes place in the manner hereinafter described, of the shaft w^0 a groove u in the 75 same is turned toward the pawl 7, so that the latter can then slip through the same.

The rocking lever 3 is provided with a toothed arc 9, which engages with a toothed wheel 10, the axle 11 of which carries the numbered drums 12 and 13 of the indicating apparatus. The figures on the numbered drums 12 and 13 are visible through openings 14 and 15 of the casing 16, one opening being turned toward the purchaser and the other toward the seller. On the rotation of the rocking lever 3 the devices herein described move with them the number-drums 12 and 13, so that the required figures on the number-drums 12 and 13 become visible through the 85 apertures 14 and 15. When the rocking lever 3 is in the "0" position, the figure "0" is visible at the apertures, and when the keys l and k' are operated the figure "1" appears, and so on. The tipping or rocking shaft w^0 , 90 which locks the rocking lever 3 and the ratchet-wheel 6 in the "0" position, is connected, by means of a rod 20, with a rear shoulder 21 of the lid of the till 22 in such a manner that when the till is closed the said shaft 100 will assume the position shown in Fig. 1—that is to say, acts to lock the pawl 7. On opening the till the shaft w^0 is turned over, so that the groove u will permit the passage of the pawl, thus allowing of rotation of the 105 rocking lever 3 and of the ratchet-wheel 6.

The temporary locking of the rocking lever 3 and the number-drums 12 13 after each adjustment is effected by means of the following devices: At a suitable point in each ratchet set (I to V) there is pivoted a pawl 23 in such a manner that it is caused by the action of a spring 24 to have a tendency to bear against the toothed rim of a toothed arc 25, which is connected with the ratchet-lever 3; but it is 115 prevented from so doing while in a position of rest by means of a rotary adjusting-shaft 26. This shaft 26 is common to all the sets, Fig. 2, and is provided with a through-recess 27, such that the latter when the shaft 26 is 120 rotated allows of the entry therein of the pawl 23 of the corresponding rocking lever 3, that is being operated at the time, and allows the said pawl to engage with the teeth of the corresponding arc 25 in such a manner that a 125 rearward rotation of the rocking lever 3 is prevented. The shaft 26 carries an arm 28, which is jointed to a rod 29, that is held by a spring 30 in the position of rest in such a position that the shaft 26 lifts all the pawls 23 130 away from the corresponding toothed arcs 25. The rod 29 projects in a recess 31 of the frame A, Fig. 1. On completely opening the till 22 a pin 32, provided on the same, enters the re-

cess 31 of the frame A and thereby forces the rod 29 into the position shown in Fig. 2, whereby the shaft 26 is turned over, so as to release the pawl 23. The pawl 23 belonging to the ratchet set that is being operated at the time then engages in the adjacent toothed arc 25, whereby a backward rotation of the corresponding rocking lever 3 is prevented until on closing the till 22 the pin 32 moves out of the recess 31 and releases the rod 29, whereupon the latter is moved back into its initial position by the spring 30. While the till is open and the lid raised, the pawl 23 will engage the teeth 25 and prevent the retraction of the arm 3. The lid 22 is further preferably provided with a catch 33, which when the till is opened engages with a corresponding catch 34 of the frame A and then holds the till 22. Further, the till is also preferably provided with an alarm 35, the operating hammer 36 of which is locked by a shoulder 37 of the till 22 when the till is closed, but when the till is opened is released and is caused by a spring 38 to strike against the bell 35.

The printing apparatus is arranged upon the side of the casing A of the apparatus, and is constructed as follows: The rocking lever 3 of each ratchet set carries a toothed arc 39, Fig. 1, which engages in a corresponding toothed wheel 41, mounted on a shaft 40. Each shaft 40 carries on its end a toothed wheel 42, Fig. 9, which gears with a toothed segment 44, mounted on a shaft 43. Each toothed wheel-segment 44 is connected with a type-wheel segment 45, which, as shown in Figs. 9 and 11, is provided with alternating large and small number types from "0" to "9." On the frame A there is pivoted at 46 a cover 47, which extends over all the sets I to V and which is held under the action of springs 48 49 in the position shown in Fig. 9, and also carries a printing abutment-roller 50, with rubber pad 51 and a feeding-roller 52, and is provided with a handle 53. Fixed to the support 47 at 54 is a cord 55, which passes over a pulley 57, mounted on the shaft 56. The pulley 57 carries an arm 58, with ink-pads 59, which extend over all the sets and which can be depressed, as indicated by dotted arrows, when the support 47 is raised, by means of the handle 53 through the medium of the cord 55, onto the types of the type-wheel arc 45 that is being operated at the time, while when the support 47 is released the said pads are shot back into the position shown in Fig. 9 by means of a spring 60, Fig. 11. Around the abutment-roller 50 there is led a paper strip 62, running off from the pulley 61. Through a slot 63 a price-ticket or receipt-form 64 can be inserted, which is then pressed against the rubber pad 51. The printing of the paper strip 62 and of the price-ticket 64 is effected first by raising the support so that the ink-pads 59 are pressed down upon the types of the type-arcs 45 that are presented at the time, and then by depressing the sup-

port 47 so that the paper strip 62 and the price-ticket 64 are pressed upon the types, which are provided with ink, Fig. 8. When a type-wheel arc 45 is in the "0" position, the printing apparatus will strike upon the type "0," whereas on operating any one rocking lever 3 the corresponding type-wheel arc 45 will be rotated to a similar extent and the type corresponding to this stroke will enter in the path of the printing apparatus. The type-wheel arcs may obviously be provided at suitable points with types for the designations of units of value—such as, for example, "£," "s," "d," "§," "¢." The ratchet mechanism for advancing the paper strip 62 is not shown in the drawings. It may obviously be made of any suitable construction. In order to prevent access to the printing parts during the printing operation, and thus to prevent tampering, there are provided in the casing 47 prongs 65, which, after depression of the casing 47, project between the rims of the type-wheels, and thus close the printing-places toward the outside, Fig. 8. To the casing 47 there is pivoted a protective cover 66, which is capable of being moved upon a hinge and which is intended to protect the printing apparatus from dirt and dust.

The adding apparatus of each ratchet set I to V is provided with a ratchet or advancing apparatus constructed as follows: In each set the ratchet-wheel 6 gears with a toothed wheel 67, which is mounted loosely on a shaft 68, 100 that is common to all the sets I to V, Figs. 1, 3, and 7. Each toothed wheel 67 is connected with the counting-disk 69 of the corresponding set, which is provided with any desired number of type-numerals. In the arrangement shown in the drawings each counting-disk is provided with twenty types, so that each half-revolution of a counting-disk corresponds to the numbers "0" to "9." Each counting-disk is provided on its facing the 110 numbering-disk of the preceding ratchet set (indicating a smaller value) with a circle of uniformly-distributed pins or teeth 70. The ratchet apparatus is now such that at every completion of a row of types of a counting-disk—that is to say, on the completion of the path from the highest number "9" to the lowest number "0"—the counting-disk of the next following ratchet set (indicating a higher value) is advanced through a distance equal 115 to the width of one tooth—that is to say, to the extent of one type-numeral. In the arrangement shown this operation takes place after each half-revolution of each counting-disk. The means for carrying out this operation are well known and may be of any desired construction.

In the apparatus shown the step-by-step advance of every two coöperating sets—such as, for example, I and II—is effected by means 130 of the levers 72, which are capable of rotating on shafts 71 and of which each is provided in the usual manner with a pawl 74 and is drawn by a spring 75 in the direction toward

the axle 68 of the counting-disk. Each lever 72 carries at its upper end a pin 76, which takes in a groove 77 of the corresponding counting-disk 69. The pawl 74 of the lever 72 of one set—for example, I—is so arranged that it can coöperate with the tooth or pins 70 of the counting-disk 69 of the next following set II. The groove 77 of each counting-disk 69 rises gradually from the “0” point up to the place corresponding to the highest number and then assumes the form of a radially-directed slot 78. In the apparatus shown the groove 77 of the double series of numbers of the counting-disks consists of two similar branches adjoining one another. So long as the pin 76 slides in the rising part of the groove 77 the corresponding lever 72 is pressed outwardly, so that the pawl 74 remains out of engagement with the pins 70 of the next counting-disk; but, however, as soon as the pin 76 enters one of the radially-directed slots 78 of the corresponding numbering-disk 69, Fig. 6, the lever 72 is drawn inward by the spring 75, whereby the next following counting-disk is moved along to the extent of one tooth. The counting-disk 69, belonging to the pawl-lever 72, which is operating at the time, is also turned to “0.” On further rotation of the same the pin 76 enters again the rising portion of the groove 77, so that the pawl-lever 72 is pressed outwardly and the pawl 74 is placed out of operation.

In the step-by-step advancing mechanism hereinbefore described it may easily happen that after the advance is effected the counting-disk that effects the advance, or that one which is thrown into action, or both disks, may be rotated farther than necessary by the action of their inertia, which produces an incorrect operation of the apparatus. This drawback is obviated according to this invention by means of the following arrangement: In each ratchet (I to V) there is mounted, so as to rotate upon a boss 79 of the lever 72, which effects the advance, a pendulum-pawl 80 in such a manner that its upper end, when in a state of rest, is situated close to the path of the pins 70 of the counting-disk 50 which is to be advanced, but out of engagement with the said pins. The lower part of each pendulum-pawl 80 is so constructed that when the pawl moves rapidly the said part has a tendency to remain in its position, so that it follows the direction of movement later than the upper part of the pendulum. If now the lever 72 after the entrance of the pin 76 in one of the radial slots 78 of the corresponding disk 69 be drawn inward by the 60 spring 75, the pendulum-pawl 80 will be moved with the same, the upper part of the same entering the path of the pins 70 of the numbering-disk to be thrown into operation and so preventing further movement of the latter, Fig. 10. The lower portion of the pendulum-pawl follows the movement only after the counting-disk has been operated. By the

still continued oscillation of the lower portion of the pendulum the upper portion of the latter moves out of engagement with the pins of the numbering-disk to be thrown into gear, so that a further operation of the latter is not prevented. The apparatus may, however, be so modified that the pendulum-pawl 80 does not coöperate with the pins 70 of the numbering-disk to be thrown into gear, but with a separate series of ratchet-teeth on the same. The action of each pendulum-pawl 80 is preferably further aided in each case by a corresponding spring 81, which is so arranged that when the counting-disk to be thrown into gear is in the stationary position the said pawl enters with a curved part 82 between the pins 70 of the counting-disk to be thrown into gear, while it is pressed to one side during the advance movement by the pin which moves forward at the time, Fig. 6, and after the termination of the advance movement it enters between the advancing and the next following pin, Fig. 10, so that it offers resistance to a further rotation of the counting-disk. In order to be able to observe the numbers marked on the counting-disks, the casing 14 is provided with observation-holes, 83 Fig. 1.

The manipulation and mode of operation of the apparatus are as follows: First, the lid 22, Fig. 1, is raised, whereby the alarm 35 is sounded. After the completed stroke of the lid 22 the catch 33 of the same engages in the corresponding catch 34 of the frame A, so that the lid 22 is firmly held. At the same time the pin 32 of the cover 22 has entered in the recess 31 of the frame A and the rod 29 has been moved forward and the spindle 26 has been turned over in such a manner that its groove 27 releases the pawls 23, Fig. 2. During the movement of the lid the rod 20 moves so that the shaft w^6 is turned over in such a manner as to bring its recess u into the path of the pawls 7 and thus allow of the rotation of the rocking lever 3 of any one set I to V. Then the press-knob—for instance, k^7 —corresponding to the number to be indicated is pressed, Fig. 4, whereby the corresponding tipping shaft w^7 is turned over in such a manner as to limit the scope of the rocking lever 3. If now the key 1 of any one set be depressed, the corresponding rocking lever 3 will be rotated as far as the shaft w^7 . By means of the corresponding tooth arc 9, with toothed wheel 10, the number-drums 12 13 are carried along, so that the figure “7” is rendered visible in the observation-holes 14 15 of the casing 16 for the purpose of being read off and checked by the purchaser and the seller. By means of the pawl 5 of the operated rocking lever 3 the corresponding ratchet-wheel 6 of the adding apparatus is also moved, whereby the corresponding number-disk 88 is advanced to a corresponding extent. After the release of the press-knob k^7 by the operator removing pressure therefrom the pawl 23 holds the rocking lever 3 and the num-

ber-drums 12 13 until the lid 22 is closed. Thus the numbers appearing in the observation-holes 14 and 15 remain visible for a time, so that any further alteration in the favor of the seller of the amounts shown is prevented. After the release of the press-knob k^5 then any further desired set can be operated in the same manner. If the number "0" is to be indicated in one set, then of course the said set must remain in the position of rest. If in a set the number "9" is to be shown and added up, then only the key 1 is to be depressed, because the press-knob k^9 , as already mentioned, is "blind," and the stroke of the rocking lever 3 is then limited by the fixed shaft w^9 . As soon as one of the number-disks 69 of any one set moves its prescribed amount the ratchet mechanism, Figs. 6, 7, and 10, hereinbefore described, acts to advance the number-disk of the next following set to the extent of one number. When the number-disks of the adding apparatus are in their limit positions, any suitable signaling or indicating device may be operated in a suitable manner, whereupon the numbering-disks can be moved by hand or automatically in a suitable manner back into the zero position. After the operation of the ratchet sets in any desired manner the casing 47 is raised, so as to turn the ink-pads 59, Figs. 8 and 9, over, whereby the types (which present themselves at the time) of the type-wheel arcs 45, which are moved in the described manner by the rotation of the rocking levers 3, are provided with ink. The casing 47 for the printing apparatus 50 51 52 is depressed, Fig. 8, whereby the checking-strip 62 and the price-ticket 84, which is to be delivered to the purchaser, are printed in accordance with the adjustment at the time. After the release of the casing 47, which is moved by the springs 48 49 into its normal position, the price-ticket 84 can be delivered to the purchaser. After this operation the lid 22 is again closed, whereby the locking devices 23 of the rocking levers 3 are released by the return movement of the rods 29 in the manner described, and the rocking levers 3 are returned, together with the number-drums 12 13, by means of the springs 18 into the "0" position, Fig. 1, while the movement beyond the "0" position is prevented by the stops 19. The ratchet-wheels 6 and the number-disks 69 of the adding apparatus are not moved back automatically into their initial position, but move on continuously, so that the several amounts indicated by the apparatus are continually added up by the adding apparatus.

The tampering of the machine cannot be effective, because the operation of the adding apparatus takes place only after the disengagement of the locking devices w . The arrangement in this case may be made such that the turning back of the ratchet-wheels 6 and number-disks 69 can be effected only with the aid of special operating devices, keys, or the like, which are kept in the custody of the pro-

prietor of the business or of a confidential employee. The cash-register herein described affords the possibility not only by uncovering the observation-holes 83, Fig. 1, of ascertaining the total amount of the amounts paid in, but also checking the several amounts by the sum total from the paper strip 62 after the removal of the latter from the apparatus. It will be readily understood that the cash-register herein described may be variously modified in respect of its construction while retaining the principle of the invention. For instance, instead of five ratchet sets, as shown, any desired number of such sets may be employed. The lid 22, which serves to effect the locking and unlocking of the rocking lever 3, may be replaced by equivalent means—for example, by a handle or the like.

Having now particularly described and ascertained the nature of this invention, I declare that what I claim, and wish to secure by Letters Patent, is—

1. In a cash-register, an adding device provided with a ratchet-wheel 6 and devices for indicating the separate amounts paid in said devices being operated by means of a rotatable rocking lever 3 coöperating with ratchet-wheel 6, in combination with means for the purpose of limiting the stroke of the rocking lever 3 of the indicating device the stop-keys $k' k^9$ for operating the limiting means and the keys independent of the stop-keys for operating the indicating mechanism.

2. In a cash-register an adding device provided with a ratchet-wheel 6 and devices for indicating the separate amounts paid in, consisting essentially of a rocking lever 3 capable of rotating, mounted loosely on the shaft 2 of said ratchet-wheel 6, and coöperating therewith (by means of pawl 5), and of number-drums 12, 13 operated by the said rocking lever, in combination with means for limiting the stroke of the rocking lever 3 in accordance with the value of any desired key $k' k^9$ consisting of tipping shafts $w' w^8$ which when in one position, gives free passage to a locking device 7 which is provided on the rocking lever 3 and which by depressing the keys $k' k^9$ is moved into a position in which it will block the path of the lever-locking device 7 and thus prevent further rotation of the rocking lever 3, and in which the outermost on the tipping shafts k^9 is made fixed so that it limits the greatest stroke of the rocking lever 3, substantially as hereinbefore described and for the purpose specified.

3. In a cash-register, an adding device provided with a ratchet-wheel 6, and devices operated by means of a rocking lever 3 coöperating with the ratchet-wheel 6, for indicating the separate amounts paid in, in combination with a lid 22 of a money-till, and with means for preventing a rotation of the rocking lever 3 when the lid 22 is closed and for allowing such rotation only when the lid is opened, substantially as described and shown.

4. In a cash-register, an adding device pro-

vided with a ratchet-wheel 6 and devices for indicating the separate amounts paid in, operated by means of a rocking lever 3 coöperating with ratchet-wheel 6, in combination 5 with the lid 22 of a money-till which when it is in its closed position sets by means of suitable mechanism 20, 21, to hold a tipping shaft w^0 provided with a recess w^0 in such a position that it blocks the path of a pawl 7 attached to the rocking lever 3 and thereby prevents the rocking lever 3 from rotating out of the "0" position, while when the lid 22 is opened the tipping shaft w^0 is rotated in such a manner as to allow the pawl 7 to 10 pass through its recess w^0 , substantially as hereinbefore described and for the purpose specified.

5. In a cash-register, the till, an adding device provided with a ratchet-wheel 6 and devices for indicating the separate amounts paid in, operated by means of a rocking lever 3 coöperating with ratchet-wheel 6, in combination with means for the purpose of effecting a temporary locking of the backward rotation 20 of the rocking lever 3, in the actuation of said rocking lever, and controlling means for said lock operated by the opening or closing of the till, substantially as hereinbefore described and for the purpose specified.

30 6. In a cash-register, an adding device provided with a ratchet-wheel 6 and device for indicating the separate amounts paid in, operated by means of a rocking lever 3 coöperating with the ratchet-wheel 6, in combination 35 with the lid 22 of a money-till and with locking devices 23 for the rocking lever 3 which, when the lid 22 is closed, are raised by a tipping shaft 26 with groove 27 away from the rocking lever 3, while when the lid 22 is 40 opened, the said locking devices are freed by suitable mechanism 28, 29, 32 (which cause a rotation of the tipping shaft 26) by means of the groove 27 of the tipping shaft 26, so that said locking devices will, when the rocking 45 lever 3 is operated, cause a locking of the same against rearward rotation which locking

ceases only when the lid 22 is closed, substantially as hereinbefore described and for the purpose specified.

7. In a cash-register, an adding device, the 50 ratchet-wheel 6 connected thereto, means for operating said ratchet-wheel, the rack 39 moving with the said wheel, the type-form, the rack thereon, the gear connection between the said racks, the pivoted casing 47 carrying the 55 paper roll, and the printing-roller 50, and guide-roller 52, and the inking-pads, the said casing being arranged to be raised and lowered, substantially as described.

8. In a cash-register, an adding device provided with any desired number of counting-disks 69 and driven by means of a ratchet-wheel 6, and devices for indicating the separate amounts paid in, operated by means of a rocking lever 3 coöperating with the ratchet-wheel 6, in combination with means for effecting a step-by-step advance of the counting-disks 69 relatively to each other, and also with means for the purpose of preventing automatic further rotation of the counting-disks 69 by reason of their momentum at the termination of the advancing movement, consisting of a pendulum-pawl 80 which is connected with the ratchet device 72 in such a manner that it is moved with the latter by the advance movement of the same, so that its upper portion engages in a ring of teeth or pins 70 of the counting-disks 69 which is to be thrown into gear, and the lower part of which pawl is so arranged that it follows this movement later than the upper portion which effects the temporary locking of the counting-disks 69, substantially as hereinbefore described and for the purpose specified.

In witness whereof I have hereunto signed 85 my name in the presence of two subscribing witnesses.

EDUARD RUNGE.
